UNITED STATES PATENT OFFICE.

EUGENE ALLEN, OF CLARION, IOWA, ASSIGNOR OF ONE-FOURTH TO LEONARD J. LESTER, OF CLARION, IOWA.

METHOD OF AND MEANS FOR CLEANING AND REPAIRING CRANK-CASE OIL TUBES.

Application filed June 6, 1921. Serial No. 475,529.

To all whom it may concern:

Be it known that I, EUGENE ALLEN, a citizen of the United States of America, and resident of Clarion, Wright County, Iowa, 5 have invented a new and useful Method of and Means for Cleaning and Repairing Crank-Case Oil Tubes, of which the following is a specification.

An object of this invention is to provide 10 an improved method of cleaning and freeing an oil tube which has become clogged in use.

Another object of this invention is to provide improved means for repairing a crank-case oil tube which has been cleaned by the 15 method herein described.

Another object of this invention is to provide an improved method of repairing an oil tube which has become damaged and clogged or susceptible of clogging in use.

Another object of this invention is to provide an improved method and means for cleaning and repairing an oil-tube through the use of unskilled labor.

My invention consists in the method and 25 means hereinafter set forth, pointed out in the claims and illustrated by the accompanying drawing, in which—

Figure 1 is an elevation, partly in section, illustrating my improved device mounted 30 in a crank-case as required for practical use. Figures 2, 3 and 4 are detail views of the oil-tube and repair therefor.

In the construction of the device as shown the numeral 10 designates the major portion 35 of an oil-tube of common form employed in a well-known make of automobile and supported in an inclined position in a crank-case 11. An extension member 12 is mounted in telescoping relation on the forward 40 end portion of the tube 10 and is formed with a forward end portion 13, reduced in diameter, preferably by spinning, adapted to be received and supported in the front wall of the crank-case 11. A stop collar or 45 clamp 14 is mounted adjustably on the tube 10 and is adapted to engage the rear end of the extension member 12 and limit rearward movement thereof, thus retaining the reduced end portion 13 thereof in its seat in 50 the front wall.

When an oil-tube is clogged or the forward end portion thereof becomes damaged and made susceptible of clogging, such as sometimes occurs through blows thereon by 55 a broken connecting rod, it is customary to

remove the timing plate from the front of the crank-case (having first removed the radiator) and blow out the contents of the tube rearwardly by application of an air-pipe to the front end of the tube, or, by 60 lifting out and dismantling the crank-case to substitute another and perfect oil-tube; which operations are of varying but considerable magnitude and expense and require 65 skilled labor in the performance thereof.

My improved method of cleaning a clogged oil-tube or repairing one that is dented and damaged in the forward portion thereof, is as follows: First remove the bottom plate of the crank-case; then cut off the 70 forward portion of the oil-tube to an extent of about six linear inches through the use of a hack-saw inserted and operated through the opening in the bottom of the crank-case produced by removing the bottom plate; 75 then removing the piece cut-off, being the forward end portion of the tube; then blowing out the contents of the remaining tube 10 rearwardly by applying an air-pipe to the cut forward end thereof; then applying 80 the set collar loosely to the tube 10; then telescoping an extension member 12 on the tube 10, introducing said member through the open bottom; then advancing the extension member 12 so that its end portion 13 85 seats in the hole in the front wall previously occupied by the forward end of the piece of tube removed; then advancing the set collar 14 into abutting relation with the rear end of the extension member 12 and clamping 90 it to the tube 10; and then replacing and securing the bottom plate on the crank-case.

This method does not comprehend the removal and replacement or substitution of the entire tube, which may be done extraneous to 95 this invention.

The method above described may be carried out by unskilled labor readily, conveniently and at minimum expense.

I claim as my invention—

1. The method of cleaning a crank-case oil-tube, which consists in removing a bottom-plate from a crank-case, cutting off and removing the forward portion of an oil-tube in said crank-case, blowing out rearwardly 105 the contents of the remaining portion of the oil-tube, applying a stop-device to the last said portion of the oil-tube, applying a telescoping extension member to the front end of said remaining portion of the oil-tube, ad- 110

justing the stop device into abutting relation with said extension member, and replacing said bottom plate.

2. The method of repairing an oil-tube which is damaged in its forward portion, which consists in removing a bottom-plate from a crank-case, cutting off and removing the damaged portion of an oil-tube in said crank-case, applying a telescoping extension member to the front end of the remaining portion of the oil-tube, and replacing said bottom plate.

3. The combination with an oil-tube from which a portion has been removed, of a stop-collar mounted adjustably thereon and an

extension member adapted to be mounted telescopically on said tube and abutting said stop-collar.

4. The combination with an oil-tube, of an extension member having a reduced end portion, said extension member being mounted telescopically on the forward end of said oil-tube, and means for limiting telescopic movement of said extension member in one direction on said tube.

Signed at Clarion, in the county of Wright and State of Iowa, this 21 day of May, 1921.

EUGENE ALLEN.
